UNITED STATES PATENT OFFICE.

ERNEST C. WEICK, OF SAN BERNARDINO, CALIFORNIA.

LIFTING DEVICE.

1,277,670.

Specification of Letters Patent.

Patented Sept. 3, 1918.

Application filed January 10, 1918. Serial No. 211,226.

To all whom it may concern:

Be it known that I, ERNEST C. WEICK, a citizen of the United States, residing at San Bernardino, in the county of San Bernardino and State of California, have invented certain new and useful Improvements in Lifting Devices, of which the following is a specification.

My invention relates to a lifter, particularly adapted for use as an attachment to and in connection with lavatories for the purpose of raising the plug which usually closes the outlet or drain opening.

The improvements are particularly advantageous in that they provide a means whereby the plug is moved a distance away from the outlet opening of the lavatory and will not therefore in anyway affect the free outflow of water and so that the hands may be brought into the path of flow of rinsing water after the washing operation, and which rinsing water flows into the lavatory basin and into the washing water, so that the outlet may be uncovered without dipping the hands into the water within the basin, soiled through the washing operation.

I particularly aim to provide a supporting means for the lifter which is attachable to the faucets of the lavatory; one having a lever as the principal means for lifting the plug and one having a catch associated with the lever to maintain it in an elevated or raised position.

With the above and additional objects and advantages, such as will appear as the description progresses hereinafter, the invention has been embodied in one improved form as illustrated in the accompanying drawings, wherein:

40 Figure 1 is a plan view of a lavatory having my improvements associated therewith;

Fig. 2 is a top or plan view of the sink lifting device;

Fig. 3 is a front elevation of the improved lifting device;

Fig. 4 is a cross sectional view on the line 4—4 of Fig. 3, and

Fig. 5 is a cross sectional view on the line 5—5 of Fig. 3.

50 Referring specifically to the drawings, a lavatory or basin is shown at 6 with which usual water supply faucets 7 and 8, one of which admits cold water and the other hot water in the usual manner. These parts are to be taken as conventional and are shown

merely to exemplify the attachment and operation of my improvements.

A rod or bar forms the base of my improvement and is designated 8', preferably being round in cross section and having one end formed into a hook at 9. The other end of this bar or rod 8' is straight and provided with screw threads 10 on which a nut 11 rides. Nut 11 rides against a hook 12 having a sleeve 13 which is freely slidable over the rod 8' and the screw threads 10. Hook 9 for instance is adapted to engage a suitable portion of the faucet 8 while hook 12 is adapted to engage a suitable portion of the faucet 7. When these hooks are brought into engagement with the faucets and bridging them as shown in Fig. 1, nut 11 is tightened to rigidly clamp the parts to the faucets.

Slidable longitudinally of the rod 8' and fulcrumed thereon, is a lever having an elongated sleeve 14 directly mounted on the rod 8'. A crank 15 extends from the lever on one side while a handle or crank 16 extends from the lever on the other side. An eyelet 17 connected to the crank 15 forms a means to which a chain or other flexible element 18 is attached and from which it is suspended. Attached to the lower end of this chain, is the plug or closure 19, which rests over and closes the outlet opening of the lavatory. It will be realized, that as the lever 14, through manipulation of its handle 16, turns in one direction, the plug 19 will be lowered into closing engagement with the outlet opening, while if the handle 16 is turned in the opposite direction, said closure will be lifted. I wish to particularly provide a means whereby the lever may be fastened in position raising the closure 19, so that the closure will not in anyway interfere with the free outflow of water from the lavatory. To this end, a short sleeve 20 is rigidly secured to the rod 8' and with which is integrally formed the lug 21. This lug is spaced from the rod 8' as best shown in Fig. 2. By reason of the fact that the lever is slidable along the rod 8' and turnable, the handle 16 may be moved beneath the lug 21 as shown in Fig. 5 and by sliding movement of the lever, securely fastened beneath the lug 21, maintaining the closure in an elevated position.

Since minor changes may be desired, it is to be understood that since I have shown but

one preferred embodiment, changes may be resorted to within the spirit and scope of the invention as defined by appended claims.

What is claimed is:—

- 5 1. A lifting device having a mounting bar, a fastening lug mounted on the bar, attaching means associated with the bar for engagement with fixtures, and a lifting bar freely movable along the bar and into engagement with the lug for fastening in an adjusted position.
- 10 2. A lifting device having a mounting bar, attaching means therefor, a lug mounted on the bar, a lifting lever mounted on the bar and freely movable thereon, and a crank extending from said lever movable beneath the lug for fastening in an adjusted position.
- 15 3. A lifting device having a mounting bar, attaching means therefor, a lug mounted on the bar, a lifting lever mounted on the bar and freely movable thereon, a crank connected to the lever movable beneath the lug for fastening in an adjusted position, and means acting in conjunction with the lifting lever and the crank for elevating the article to be lifted.
- 20 4. A lifting device having a bar provided with a hook at one end, a hook member adjustably mounted on the bar at the opposite end thereof, said hooks acting in conjunction with each other for detachably securing the bar to fixtures, a nut abutting the
- 25

last mentioned hook member, and lifting means freely movable along the bar.

35

5. A lifting device having a mounting bar, a fastening lug mounted on the bar, attaching means associated with the bar for detachably securing it to fixtures, a lifting bar freely movable along the bar and into engagement with the lug for fastening in an adjusted position.

40

6. A lifting device comprising a mounting bar, a lug associated with the bar, a lever fulcrumed on the bar and slidably longitudinally thereon, said lever having a crank, said crank being movable into fastening relation beneath said lug, and a member to be lifted connected to said sleeve.

45

7. A lifting device comprising a rod formed into a hook at one end, adjustable hook means mounted on the bar adjacent the opposite end, a lug rigidly extending from the bar, a sleeve slidable and turnable on the bar, an operating crank extending from the sleeve and movable to a position beneath the lug for fastening, a second crank extending from the lug, and a flexible means extending from the second sleeve to engage the article to be lifted.

50

In testimony whereof I affix my signature in presence of two witnesses.

ERNEST C. WEICK.
